UNITED STATES PATENT OFFICE.

WILLIAM W. BERRY, OF SCRANTON, PENNSYLVANIA.

DESIGN FOR A SPOON.

SPECIFICATION forming part of Design No. 21,699, dated July 12, 1892.

Application filed June 2, 1892. Serial No. 435,312. Term of patent 7 years.

To all whom it may concern:

Be it known that I, WILLIAM W. BERRY, a citizen of the United States, residing at Scranton, in the county of Lackawanna and State 5 of Pennsylvania, have invented and produced a new and original Design for Spoons, of which the following is a specification, reference being had to the accompanying drawing, forming a part thereof.

10 The drawing is a front elevation of a spoon, showing my design applied thereto.

The main feature of my design consists in a spoon having thereon the representation of a spoked wheel with radially or tangentially 15 disposed pinions or wings applied to the hub thereof. This device I apply to the extremity of the spoon-handle, and in connection therewith I also apply to the handle of the spoon the representation of a bicycle having mounted 20 thereon a wheelman.

A is the rim, and B is the hub, of a wheel having spokes C connecting said hub and rim. Pinions or wings D, preferably three in number, are applied to the hub and disposed either radially or tangentially thereto. This 25 wheel is applied to the extremity of the handle of the spoon I, while upon the handle of the spoon, in close proximity to said wheel, is a bicycle E, having a rider mounted thereupon.

3a

What I claim is—

The design for a spoon, as herein shown and described.

In testimony whereof I affix my signature in presence of two witnesses.

WILLIAM W. BERRY.
